(57) **CLAIM**

The ornamental design for a decanter set, as shown and described.

DESCRIPTION

FIG. 1 is a top, front and right side perspective view of a decanter set showing my new design;

FIG. 2 is a rear and left side perspective view thereof;

FIG. 3 is a bottom and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1; and, FIG. 11 is an enlarged view of portion 11 in FIG. 2.

The evenly dashed broken lines in FIG. 3 and FIG. 9 illustrate portions of the decanter set. the unevenly dashed broken lines define the boundaries of enlarged views. None of broken lines form part of the claimed design.
